UNITED STATES PATENT OFFICE

EDWARD C. HEGG, OF BUFFALO, NEW YORK, ASSIGNOR TO MOJONNIER BROS. CO., A CORPORATION OF ILLINOIS

WRAPPING MACHINE PAPER FEED MECHANISM

Original application filed May 10, 1927, Serial No. 190,359. Divided and this application filed April 6, 1929. Serial No. 353,044.

This invention relates to a machine for cutting a slab or block of material into sections or slices and wrapping the same in paper suitable for sale to the retail trade, and although this machine is primarily designed for cutting ice-cream slabs or blocks in this manner and wrapping them preparatory to turning the same over to customers, it obviously can be used for slicing and wrapping other materials preparatory to dispensing the same.

It is the object of this invention to provide a machine capable of performing these functions which is compact in construction, efficient and economical in operation and capable of handling a comparatively large amount of material conveniently, and expeditiously.

The present application is a division of my prior application Serial, No. 190,359 filed May 10, 1927. The paper handling features are claimed more particularly herein.

In the accompanying drawings:—

25 Figure 1 is a side elevation of a cutting and wrapping machine embodying my invention with parts of the enclosure broken away so as to show the internal mechanism.

30 Figure 2 is a top plan view of the same with parts broken away to show the internal mechanism.

35 Figure 3 is a front elevation of the same, on an enlarged scale, showing parts broken away and in section for exposing the internal mechanism.

40 Figure 4 is a fragmentary view similar to Fig. 3 but showing more particularly the mechanism for wrapping a sheet around the sections of material.

45 Figure 5 is a vertical transverse section, on an enlarged scale, taken on line 5—5 Fig. 1 and showing more particularly the mechanism whereby the block or slab of material is cut into sections or slices.

50 Figure 6 is a fragmentary front elevation of one of the grippers and adjacent parts of the paper feeding mechanism on the left side of the machine.

55 Figure 7 is a top plan view of the same.

50 Figure 8 is an edge view of the gripper and

adjacent part of the left hand paper feeding mechanism, shown in Fig. 6.

Figure 9 is an end view of one of the left hand paper grippers detached from its carrier.

55 Figure 10 is a vertical cross section taken on line 10—10 Fig. 2.

Figures 11, 12, 13, 14, and 15 are diagrammatic views illustrating different positions of parts of the mechanism whereby a sheet of 60 paper or similar material is wrapped around a section or slice of material.

Figure 16 is a fragmentary front elevation of the plunger and adjacent parts of the mechanism whereby a sheet of paper is 65 wrapped around a section of the material.

Figure 17 is a fragmentary longitudinal section taken on line 17—17 Fig. 16.

Figure 18 is a fragmentary vertical longitudinal section of the right hand portion of 70 the wrapping mechanism and adjacent parts, on an enlarged scale.

Figure 19 is a front elevation of the closing trip arm on adjacent parts of the paper feed mechanism on the right hand side of the machine which controls the operation of feeding the paper, depending upon whether the block of material has been initially advanced to a predetermined position.

75 Figure 20 is an end view partly in section, on an enlarged scale, of one of the grippers of the right hand paper feed mechanism showing the same in its open position.

Figure 21 is a similar view showing the gripper in its closed position in which it grips 85 the web of paper which is to be advanced to the wrapping position.

Figure 22 is a perspective view of a cake or slice of material which has been wrapped in the machine forming the subject of this 90 invention.

Similar characters of reference indicate corresponding parts in the several figures of the drawings:—

95 The numeral 30 represents the main frame of the machine which may be of any suitable construction to support the various working parts of the machine. On the upper part of this frame and at the rear end thereof the same is provided with a horizontal table 31 100

upon which is adapted to be supported a block or slab of material 32 such as a block of ice cream, preparatory to cutting the same up into sections and wrapping the sections 5 successfully in sheets of paper. The forward movement of this block of material may be effected step by step through the medium of a feed mechanism such as is disclosed in my prior parent application Serial No. 10 190,359, or the same may be fed by hand.

Since the subject matter claimed more particularly in the present case is the paper handling and immediately associated mechanism, it will not be necessary to a disclosure of that 15 invention to show and describe herein the material feed mechanism of my parent application. Consequently it may be assumed for the purposes of the present disclosure that the slab or block of material is fed by hand. 20 In such case the slices 29 will be cut by proper step by step advances of the follower 33 acting against the rear of the block or slab 32. For an understanding of the automatic material feed mechanism, reference should be 25 had to my said parent case.

The numeral 33 represents the follower which is arranged transversely above the feed table 31 and moved forwardly lengthwise thereof in engagement with the rear end of 30 the block of material for advancing the latter toward the cutting mechanism and also capable of being retracted into its rearmost position for engaging with a new block when the cutting of the preceding block has been 35 completed or nearly completed.

The main driving shaft 42 of the machine is journaled horizontally and lengthwise in the lower part of the main frame and is rotated so that it makes one turn for every complete cycle of operations of the machine. 40 Although this driving shaft may be operated in any suitable manner and from any suitable source, it is preferable to drive the same from an electric motor 43 which is mounted on the lower rear part of the main frame. Motion 45 may be transmitted from this motor to the main driving shaft 42 by the driving belt 44 passing around pulleys 45 and 46 which are secured to the shaft 47 of the motor and a countershaft 48 arranged transversely below the main shaft 42, and a worm gearing consisting of a worm pinion 49 secured to the countershaft 48 and meshing with the worm wheel 50 on the main driving shaft, as best 55 shown in Figs. 1 and 3. For the purpose of starting and stopping the machine without interrupting the motion of the motor, a clutch 51 is preferably employed which is interposed between the main driving shaft 42 and the driven worm wheel 50 and which is operated by means of a shifting lever 52, as shown in Fig. 1.

As the block of material reaches the end of each step during its forward feeding movement the front end of this block projects

beyond the front end of the table 31 and either engages with or is close to an upright front wall or stop 70 which latter is separated from the front edge of the table 31 by an intervening space which forms a vertical well 71. After the block of material has been thus advanced so that its front end projects beyond the front end of the feed table 31, this projecting part of the block is operated upon by a cutter mechanism for severing a section 75 or slice of material from the block. This cutter mechanism may be variously organized but in its preferred form the same comprises two cutter blades 72, 73, which are arranged vertically and are adapted to move 80 transversely toward and from each other across the path of the block of material so that in the closed position of these cutters the opposing upright edges of the same practically meet at the center of the path of material, while in the open position of the blades the same are retracted laterally from opposite sides of this path so as to not obstruct the same and permit of feeding the block forwardly. 85

As best shown in Fig. 5, the cutter 72 is mounted on the upper arm 74 of an elbow lever which is pivoted on the main frame by a horizontal longitudinal pivot and the cutter 73 is secured to the upper arm 75 of a three-armed lever which is pivoted by a horizontal longitudinal pivot to the main frame. These levers are caused to move in unison so that their cutter blades approach the center of the path of the block and move away from the same at the same time by a link 76 connecting the inwardly projecting lower arm 77 of the lever supporting the left hand blade 72 with an inwardly projecting central arm 78 of the lever supporting the right hand blade 73, and a rotary cam 79 secured to the driving shaft 42 and engaging with the lower arm 80 of the lever supporting the right hand blade 73 as best shown in Figs. 1, 3 and 5. 100

After a section or slice has been cut off from the front end of the block, the same is shifted to the mechanism which operates to wrap a sheet of paper around the same. This mechanism in the preferred construction comprises an elevator 81 which is normally lowered in the well 71 with its upper side substantially flush with the top of the feed table 31 so that the block of ice cream or other material when advanced, will project with its foremost portion over the upper side of the elevator 81, then the latter is raised so as to lift the foremost part of the block of material which has been severed in the form of a slice or cake from the remainder of the block until this section is arranged above the body of the material and horizontally in line with the device which operates to wrap a sheet of paper around this section. This elevator is raised and lowered in proper 110 115 120 125 130

timing with the movement of the section cutter and block feeder and this is preferably accomplished by mounting this elevator on the upper end of a lifting rod 82 which is 5 suitably guided on the main frame and engages its lower end with a lifting cam 83 which is mounted on the driving shaft 42 so as to be rotated thereby.

In Fig. 11 this elevator is shown in its 10 lowermost position which it occupies while the block of material is being fed over the same, and in Fig. 12 this elevator is represented in its highest position which it assumes when the section of material severed 15 from the body of the same has been elevated in proper position to be acted upon by the wrapping mechanism.

In the manufacture of ice cream or similar material in the form of blocks or slabs, the 20 cross section of the same is usually of oblong form and of twice the area in which ice cream or similar material is usually sold in brick form. It is therefore proposed in the present machine to again divide the sections 25 which are removed from the block of material into two smaller cakes or slices of equal size. To accomplish this without involving the use of any additional movable parts, a dividing blade 84 is provided which is arranged in an upright and longitudinal position 30 above the well 71 and mounted on the adjacent part of the main frame so that when the section of material removed from the main block is lifted, this section will be engaged with this dividing blade 84 and cut thereby into two cakes or slices of equal dimensions by the time the section has been elevated into its highest position by the elevator.

40 In order to prevent the lower edge of this dividing blade from being injured or interfering with the operation of the elevator the central part of the latter is provided with a longitudinal notch or recess 85 as shown 45 in Fig. 5, which receives the lower edge of the dividing blade 84 and enables the latter to effect a clean cut or division between the two smaller cakes or slices of material which have been elevated preparatory to wrapping 50 them in paper.

After a section of material has been thus elevated and divided into two smaller cakes or slices, the same are acted upon by a wrapping mechanism which operates to wrap 55 sheets of paper individually around the cakes or slices of material so as to cover the upper and lower edges and the front and rear flat sides of each cake or slice, leaving the side edges exposed.

60 In the main, this wrapping mechanism is duplicated, the main parts of each mechanism serving to wrap one cake or slice of a pair and the following description, in the main, will therefore apply to the two sections 65 of this wrapping mechanism whereby

two slices or cakes of material are wrapped at the same time:—

The numeral 86 represents a tubular receiver which is arranged horizontally and lengthwise immediately in rear of the place where the two cakes or slices of material come to rest when the elevator reaches the upper end of its stroke and which is adapted to receive these two slices by having the latter moved rearwardly into the same. 70 This rearward movement of these two slices or cakes of material is effected by means of a longitudinally and horizontally movable plunger 87 which is mounted on the front end of a plunger rod 88 which is guided in suitable guide-ways on the upper part of the main frame and which is reciprocated in proper synchronism with the other parts of the machine by motion derived from the driving shaft 42. The particular mechanism whereby motion is transmitted from this driving shaft to the plunger rod 88 which is shown in the drawings, comprises an upright rock shaft 89 journaled in suitable bearings on the main frame and provided at 80 its lower end with a rock arm 90 which engages with a cam 91 on the driving shaft 42, a spring 92 which holds the rock arm 90 yielding in engagement with the cam, an upper rock arm 93 arranged on the upper end of 95 the rock shaft 89 and a link 94 connecting the upper rock arm 93 with the plunger rod 88, as best shown in Figs. 1, 2, and 3. While the section of material is being lifted by the elevator 81 and cut into two smaller cakes or slices the plunger 87 is retracted rearwardly out of the path of the slices to be wrapped as shown in Fig. 11, and after these slices have reached their uppermost position, as shown in Fig. 12, the plunger is moved forwardly and pushes the slices of material from the top of the elevator into the receiver 86, as shown in Fig. 13.

Preparatory to moving each cake or slice of material from the upper end of the elevator into the receiver 86 a sheet of paper is fed downwardly so that the central part 95 of this sheet is arranged opposite the inlet of this receiver and the upper and lower ends 96 and 97 of this sheet are arranged above and below the inlet of the receiver, as shown in Fig. 11. As each cake or slice of material is pushed from the elevator into the receiver the flat front side of the slice engages with the central part 95 of the sheet of paper and as 110 this cake or slice and the sheet of paper are pushed together forwardly into the receiver the upper and lower parts of the sheet immediately adjacent to the central part 95 thereof are bent horizontally rearwardly against the 115 upper and lower edges of the cake of material by the rear edges 27, 28 of the top and bottom of the receiver 86, as shown at 98 and 99 in Figs. 13, 14, 15 and 18.

120 After the slice of material has been thus 130

pushed into the receiver 86 and while the plunger 87 is still in engagement with the rear side of the slice, a lower folding blade 100 first rises into engagement with the lower part of the sheet immediately adjacent to the lower rear corner of the slice and produces a short crimp in the same, and an upper folding blade 101 descends and engages with the upper part of the sheet immediately adjacent to the upper rear corner of the slice and also produces a short crimp in this part of the sheet, as shown in Fig. 14, thereby serving as retainers whereby the partly wrapped slice of material is held in the receiver 86 and the plunger 87 is permitted to withdraw rearwardly out of engagement from the rear side of the slice of material without liability of pulling this slice backwardly with the plunger as would be liable to occur owing to the adhesion which was produced between the same while the plunger moved the slices of material forwardly into the receiver. After the plunger has been thus withdrawn rearwardly away from the rear side of the slice of material, the lower folding blade 100 completes its upward movement and bends the lower end 97 of the sheet in the form of a flap against the rear side of the slice of material, as shown in Fig. 15 and then the upper folding blade 101 also completes its downward movement and bends or folds the upper end 96 of the sheet downwardly against the rear side of the slice of material, as shown in Fig. 15. Thereafter the lower folding blade is moved downwardly and the upper folding blade 101 is raised out of the path of the slice and the plunger as the next slice is moved from the elevator into the receiver.

Various means may be employed for obtaining this particular action of the folding blades, those shown in the drawings being suitable and comprising a lower cross-head 102 which carries the lower blade, an upper cross-head 103 which carries the upper folding blade, two upright tubular shifting rods 104 connected with opposite ends of the lower cross-head 102 and guided in guideways 105 on the main frame, a lower cross-head 106 connected to the lower ends of the tubular rods 104, upright guide rods 107 sliding in the tubular rods 104 and connected at their upper ends with the upper cross-head 103, a lower cross-head 108 connected with the lower ends of the guide rods 107, and two cams 109, 110 formed on a disk 111 which is secured to the driving shaft 42 and engaging with the lower cross-heads 108 and 106 respectively, as shown in Fig. 4. As the cams 109 and 110 rotate with the driving shafts, the lower and upper folding blades are moved vertically toward and from each other across the rear or inlet end of the receiver 86 and produce the holding action on the sheet of paper for wrapping the same around a slice

or cake of material in the manner which is described.

As each succeeding slice or piece of material is pushed forwardly from the elevator into the receiver and wrapped in a sheet of paper 70 the same engages with the previously wrapped slice of material and pushes the latter forwardly upon a delivery table 112 on which the several wrapped slices of material accumulate in a row preparatory to being 75 removed and dispensed to the trade or placed in a refrigerator or other container ready for distribution.

The mechanism whereby sheets of paper are supplied for wrapping the pairs of slices 80 of material at the same time may be varied in construction, but as shown in the drawings the same are preferably constructed as follows:—

The paper for the two slices of material 85 is supplied from two rolls 113 which are arranged axially in line and side by side above the plunger 87 and its actuating mechanism and mounted to turn loosely on arbors 114 which project from opposite sides of an upright plate 115 which is carried by a bracket 116 secured to the adjacent part of the main frame. The web of paper is unwound from the upper side of each of these rolls and passed forwardly and downwardly over a 90 tension roller 117 and thence into position to be engaged by a paper feeding and cutting mechanism which operates to feed the web of each roll downwardly intermittently and cuts the same into sheets of a length suitable 95 for wrapping around four surfaces or sides 100 of a slice of material as hereinbefore described.

In order to prevent the rolls of paper 113 from turning too rapidly and possibly overthrowing when the paper web is pulled therefrom, a brake device is provided which prevents such excess rotation and interference with the proper operation of the machine. This brake device preferably consists of a 110 brake arm 118 which is pivoted at its lower end on the adjacent part of the main frame so as to swing in a vertical plane and bears at its free upper end on the upper portion of one of the paper rolls, as shown in Fig. 1, and thereby exerts sufficient pressure by gravity against this roll so as to operate as a retarder to prevent too free unwinding of the web from the roll.

In order to prevent the downward pull on the lower front end of the web from tearing the same during the operation of feeding the paper from the roll to the wrapping mechanism a yielding tension device is provided for supporting the tension roll 117, 125 which tension device preferably consists of an upright tension rod 119 which is guided for vertical movement on the upper part of the main frame and is provided at its upper end with a horizontal pin 120 upon which 130

the roll 117 is pivoted, a tension spring 121 surrounding the tension rod 119 and bearing at its lower end against a shoulder 122 on the main frame, while its upper end bears 5 against a pin 123 on the tension rod, which pin also bears against a shoulder 124 on the upper part of the main frame and thereby limits the upward motion of the tension roller. When the lower front end of the 10 web of paper is pulled downwardly suddenly the tension roller 117 yields as much as required to prevent tearing of the web but when the motion of the web has been started, the tension roller is again elevated to its 15 normal position under the action of the tension spring.

Inasmuch as the two mechanisms whereby the web of paper is simultaneously fed from the two rolls of paper to the two wrapping 20 mechanisms are identical in construction so far as the main features are concerned, the following description of one of these mechanisms so far as it applies, may be taken as a description of both of these mechanisms.

25 Arranged on transversely opposite sides of a passageway 125 between the rear end of the receiver 86 and the upper part of the elevator well 71 are two feed belts 126 which are preferably of the chain type and which 30 are so mounted that they provide inner vertical operative stretches which are adapted to be moved outwardly adjacent to opposite sides of the passage 125, and vertical inoperative stretches which move upwardly adjacent the opposite outer sides of the machine, each of these belts passing with its 35 upper and lower turns around supporting sprocket wheels 127, 128 which are pivotally mounted on the adjacent parts of the main frame. These belts are caused to move intermittently in unison by motion which is transmitted thereto from the main driving shaft 42 by a train of transmitting gearing which is preferably constructed as follows:—

40 The numeral 129 represents an upright shaft journaled in suitable bearings on the front part of the machine and connected at its lower end with the driving shaft 42 with 45 intermittent driving gears 130, 131 as shown in Figs. 1 and 3. Arranged transversely and horizontally above the upright shaft 129 is a horizontal intermediate shaft 132 which is journaled on the adjacent part of the main frame and connected by a pair of bevel gears 50 55 133, 134 with the upper end of the upright shaft 129, as shown in Figs. 2 and 3. Each of the lower sprocket wheels 128 is mounted on the rear of a longitudinal shaft 135 which latter is operatively connected at its rear end 60 with the adjacent part of the horizontal shaft 132 by means of a pair of miter gears 136, 137, as shown in Figs. 1, 2 and 4. By means of this mechanism the two paper feed chains 126 are caused to move downwardly 65 with their operative inner stretches a dis-

tance equal the length of the sheet or strip of paper which is adapted to be wound around the slices of material and then remain at rest until this strip has been severed and wrapped around the slice of material, 70 which operations occur during one rotation of the main driving shaft 42. The lower front end of each web is caused to move downwardly with the adjacent operative stretch of a paper feed belt by means of a 75 plurality of grippers which are mounted at intervals on the respective feed belt and spaced at intervals thereon equal the length of a sheet or strip of paper which is to be wrapped around a slice of material. Each 80 of these grippers projects laterally from this feed belt and is adapted to engage the outer edge of the respective web of paper while the gripper is near the upper end of the operative stretch of the belt and remains attached 85 thereto until the gripper reaches the lower end of the operative stretch and is then released so that the web of paper is left in a position to be cut into proper length of sheet, and the gripper is free to return idly upward 90 with the inoperative stretch of the belt to the place of beginning the next feeding action.

95 Each of these grippers in its preferred form, as best shown in Figs. 6, 7, 8, 9, 18, 20 and 21 comprises a carrier 138 which is mounted on one of the links of the feed belt 124 and is adapted to slide at its opposite edges in a pair of vertical tracks or guideways 139, 140 which are mounted on the main frame adjacent to one side of the passageway 125, a relatively fixed front gripper jaw 141 projecting laterally from the carrier 138 and having a gripping face on its rear side, a movable rear gripping jaw 142 arranged in rear of each stationary jaw 141 100 and journaled in a bearing 143 of the carrier 138 and made cam shape in cross section so as to provide a high gripping face 144 and a low releasing face 145 on its periphery so that by turning this movable jaw about its 105 axis either its low face may be presented to the fixed gripping jaw 141 to release the paper which is arranged between these jaws as shown in Figs. 8 and 20, or to move the high face of the movable jaw opposite the fixed jaw for the purpose of gripping this sheet therebetween, as shown in Figs. 9 and 21.

110 This turning motion of the movable jaw of each gripper is effected by means of two 115 tappets 146, 147 projecting forwardly and rearwardly from the inner part of the movable gripper jaw 142. As each gripper passes with its feed belt inwardly over the top of the upper supporting wheel 127 the 120 same is open and as it begins its downward movement to the upper portion of the operative stretch of this belt these jaws move 125 downwardly along opposite sides of the adjacent outer edge of the respective web of 130

paper and under normal conditions the movable jaw of the gripper at this time is turned in a direction for presenting its high face to the companion stationary jaw and gripping the paper therebetween. The rotation of the movable jaw at this time is effected by its front tappet 146 engaging with a closing trip member 148 which at this time is arranged in the path of the front tappet 146 10 and therefore compels this tappet to be moved upwardly in order to clear the trip member 148 and thereby produce a rotary motion of the jaw 142 which operates to close the same and grip the adjacent edge 15 portion of the sheet of paper.

This gripper engages with the web of paper at the front end of the sheet or strip which is adapted to be severed from the web and wrapped around the next following 20 slice or piece of material and the engagement of this gripper with the web is effected while the same is arranged at a predetermined distance above the receiver 86 in order to leave a length of the web below this gripper which will extend vertically across the 25 rear end of the receiver 86 and a sufficient extent above and below the receiver to form a sheet which can be wrapped around the slice of material in the manner previously 30 described. After the gripper has thus engaged with the edge of the web at a distance above the receiver 86 the same comes to rest and immediately thereafter the web is severed below the gripper which has just taken 35 hold of the web so as to detach a sheet from the advancing end of the web and permit the same to be wrapped around a slice of material by means of the wrapping mechanism. After the preceding severed sheet has been 40 wrapped around a slice of material and the plunger 87 has been retracted so as to clear the passage 125, the feed belt is again moved forwardly one step so as to carry the active gripper which is now in engagement with the edge of the web of paper downwardly 45 to the lower part of the operative stretch of the feed belt at which point another length of paper has been fed so as to extend across the receiver 86 and project a sufficient distance below and above the same to form 50 another sheet which is to be subsequently wrapped around the next following slice of material. After the web has been thus fed down another length in the manner described, the gripper is released from the lower or advancing edge of the web and then the feed belt is moved forwardly another step so that the lowermost gripper which is 55 now open is carried away from the web and moved downwardly and outwardly around the respective lower supporting wheel 128 and then upwardly with the inoperative stretch of the feed belt preparatory to being 60 again moved into its operative position for

again engaging the web and advancing the same another step.

This opening of the gripper is effected by the rear tappet 147 thereof engaging an opening trip member 149 which is arranged in the path of the opening tappet 147 (see Figure 18) so that as the gripper effects the last part of its downward movement with the operative stretch of the feed belt, this tappet 147 will engage the opening trip member 149 75 and be turned from its lower position, as shown in Fig. 21 to its upper position as shown in Fig. 20, in order to clear the trip member 149. It will therefore be apparent that when the gripper is in open position its 80 closing tappet 146 is intercepted by the closing trip member 148, while the opening tappet 147 is in operative position relative to the opening trip member 149, but when the closing tappet 146 is shifted into its upper position from which it clears the closing trip member 148, then the opening tappet 147 will be moved downwardly into a position in which it will engage the opening trip member 149 during its continued movement, 85 thereby causing the gripper to be automatically closed upon the sheet while the same straddles the edge of the sheet at the beginning of an operative stroke, and to be opened for releasing the sheet at the end of an operative stroke of the gripper. 90

Means are provided whereby the paper feed mechanism will be maintained in an inoperative condition and not effect a forward feed of paper to the folding position in case the machine is operated when no pieces or slices of material are passed through the machine for the wrapping mechanism to operate upon. This condition will occur when the block or slab of material on the feed table has not been moved forwardly far enough to cut a slice therefrom which can be elevated into position for being subsequently pushed by the plunger 87 against a sheet which closes the receiver 86. The means which are provided for thus automatically controlling the feeding of the paper depending on the absence or presence of a slice of material in the proper position to be wrapped is constructed as follows:— 110

The numerals 150 represent rock shafts which are journaled horizontally and transversely in bars 151 mounted on a suitable stationary part of the machine, for example on the upper part of the front guide rails 140 120 for the paper feed belt 126, as shown in Figs. 3, 6, 7, 8, 18 and 19, so that by rocking each of the shafts 150 the respective closing trip member or finger may be moved into and out of the path of the closing tappets 146 of the 125 respective grippers. Above the front or delivery end of the feed table 31 is arranged a deflector plate 152 which in the absence of a slab or block of material is adapted to project downwardly into the path of this block 130

but which is adapted to be pushed upwardly out of this path by the block of material as the front end of the same is moved fully forward into a position in which its front end 5 is flush with the front end of the feed table 31, which movement of the deflector is utilized to control the position of the closing trip member 148 accordingly.

This deflector is preferably pivoted at its 10 rear end by means of a pin 153 on a stationary part of the main frame arranged immediately above the path of the block of material and the same is adapted to be depressed by gravity aided by a spring 154 which is 15 secured to the adjacent part of the main frame and bears against the upper side of the deflector. Motion is transmitted from this deflector by a shifting rod 155 which is pivotally connected at its lower end with an upwardly projecting lug 156 on the upper side 20 of the deflector while its upper end is connected with a rock arm 157 on the opposite end of the rock shaft 150, which carries the movable or closing trip member 148.

25 When the front end of the block of material is not flush with the front end of the feed table or substantially so, then the deflector 152 will project downwardly into the path of the block of material, as shown by dotted 30 lines in Fig. 18, whereby the closing trip member 148 will be moved downwardly and outwardly away from the path of the closing tappet 146 of the grippers and thereby avoid closing this gripper so that the same will 35 effect its downward working stroke from a position above the receiver 86 to a position below the same without carrying any paper across the inlet of the receiver. When, however, the block of material has been advanced on the feed table sufficiently far to bring its front end flush with the front end of the table or substantially so, then the deflector 152 will be shifted by the block of material into its elevated position as shown by full lines in Fig. 18, whereby the closing trip member 148 will be moved inwardly and upwardly into a position in which it will intercept the closing tappet 146 of the gripper and thus the same will be closed for gripping a web of paper so that during the subsequent stroke of the paper feed mechanism a sheet or strip of the web will be moved downwardly across the inlet of the receiver 86 into a proper position for wrapping the same around the next following slice of material.

In the absence of this automatic controlling device which would permit a continuous feed of paper regardless of whether the slice of material were presented to the wrapping mechanism the machine would become clogged with paper and necessitates not only an interruption in the working of the machine for clearing the same but also occasioning a loss of time and waste of material.

While the web is momentarily at rest after

the front end of the same has been moved downwardly one step for carrying the foremost length across the inlet of the receiver 86 and before the sheet has been released and operated upon by the folding and wrapping 70 mechanism, this foremost length of sheet is severed from the remaining portions of the web immediately below the point where the next length of web is grasped by the next following gripper. The cutting mechanism 75 whereby this is effected is best shown in Figs. 1, 2 and 3 and is constructed as follows:—

The numeral 158 represents an upper stationary cutter blade which is arranged horizontally and transversely in rear of the path 80 of the wrapping paper adjacent to the operative stretch of the respective paper feeding belt and mounted in any suitable manner on an adjacent part of the main frame. Turning in a horizontal plane and cooperat- 85 ing with the front edge of the stationary blade 158 is a movable cutter blade 159 which is pivoted at its outer end on a pivot pin 160 which is supported on the stationary blade 158, this pivoted blade being held yieldingly 90 in contact with the companion stationary blade by means of a spring 161 bearing at its lower end against a shoulder 162 on the main frame and at its upper end against the hub of the swinging blade, as best shown in Fig. 95 3. When the two cutter blades 158, 159 are separated a passageway is formed between them through which the web of paper is carried by the grippers of the respective paper feeding mechanism and after the web has 100 been fed downwardly a requisite length and has come to rest then the movable cutter blade 159 is moved backwardly across the companion stationary blade 158 thereby pro- 105 ducing a shearing cut upon the web of paper between the same which operates to sever the advancing length of the web which is to be used for wrapping a slice of material from the remaining body portion of the web. Motion for swinging this movable cutter 110 blade 159 backwardly and forwardly for cutting the sheet of paper and then again clearing the path of the web is derived from the main driving shaft 42 by a train of gearing which is preferably constructed as follows:—

The numeral 163 represents a horizontal rock shaft which is journaled transversely in suitable bearings on the main frame. On its central part this shaft is provided with a downwardly projecting rock arm 164 which engages with a cam 165 secured to the up- 2. At opposite ends this rock shaft 163 is provided with upwardly projecting rock arms 166, each of which is connected at its upper end by means of a link 167 with an inwardly projecting rock arm 168 on the hub of one of the lower cutter blades 159, as shown in Figs. 1, 2 and 3. As the cam 165 rotates in-

6 intermittently due to the action of the mutilated gears 130, 131, this motion transmitting mechanism operates the paper cutting mechanism once during each cycle of operations for severing the sheet of paper from the web which is to be used for wrapping a slice of material.

10 If no paper is fed forward to the wrapping position due to the block of material not being advanced to the proper position on the feed table then the paper cutter mechanism performs an idle operation which is without effect.

15 Inasmuch as the upper end of the sheet of material which has been severed from the web is liable to fall down and double up into a more or less irregular condition which would interfere with the proper wrapping of the same around a slice of material, means are 20 provided for retaining the upper part of the sheet of paper in its proper position relative to the folding mechanism until it is engaged by the front side of the slice of material which is to be wrapped and under the control of the folding mechanism.

Preferred means for this purpose comprise 25 a detent device consisting of a plurality of detent fingers 169 of spring metal, the lower ends of which are adapted to move forwardly 30 and backwardly toward the rear side of the upper folding blade 101 for the purpose of clamping the upper part of the sheet of paper against the same, or releasing it, a horizontal rock shaft 170 carrying the upper ends 35 of the detent fingers 169 and journaled in suitable bearings 171 on the main frame above the plunger 87, a retracting arm 172 projecting downwardly from the rock shaft 170 and adapted to engage the rear side of the plunger 87, and a spring 173 interposed between 40 the upper rear side of the retracting arm 172 and the adjacent part of the main frame, and operating to move the arm 172, rock shaft 170, and fingers 169 forwardly toward the upper 45 folding blade 101. When the plunger 87 is in its retracted position the same moves the retracting arm 172 backwardly together with the detent fingers 169 so that a clear path is formed between these detent fingers and the upper folding blade 101 through which the 50 web of paper and the grippers adapted to engage the same can pass freely.

During the first part of the forward movement of the plunger 87 which is timed to occur just before the movable blade 159 cooperates with the stationary blade 158 for severing the foremost sheet from the body of the web, the plunger 87 permits the retracting arm 172 to move forwardly from the position shown by full lines in Fig. 17, to a position shown by dotted lines in the same figure, whereby the gripping fingers 169 are permitted to move forwardly to a position shown by full lines in Fig. 17 to a position shown by 60 dotted lines in the same figure in which last

70 mentioned position the gripping fingers engage with the rear side of the upper part of the web of paper and clamp the same against the rear side of the upper folding blade 101. Immediately thereafter the operation of severing the sheet from the web by the action of the blades 158, 159 is effected but the sheet 75 will be prevented from dropping and assuming a more or less crumpled position at this time, inasmuch as it is securely clamped adjacent to its upper end against the upper folding blade 101. The upper part of the sheet is however easily withdrawn from between the detent fingers 169 and the upper folding blade 101 as the central part of the 80 sheet is engaged by the front side of the slice of material, which latter is pushed forwardly during the continued forward movement of the plunger 87 after the latter has permitted the detent fingers 169 to engage the upper folding blade. During the downward movement of the upper folding blade 101 for effecting the preliminary crease in the upper flap of the sheet, as shown in Fig. 14, the upper blade simply slides in contact with the 85 detent fingers 169 and also rises into its elevated position for the purpose of clearing the rear or inlet end of the receiver 86 without any objectionable effect.

90 During the backward or return movement 95 of the plunger 87 the same again engages the lower end of the retracting arm 172 and moves the detent fingers 169 rearwardly out of the path of the web of paper and the fingers of the feeding mechanism.

100 It will be apparent from the foregoing description that by the use of this machine a large quantity of material which is usually manufactured in blocks or slabs such as ice cream can be cut up and wrapped economically and expeditiously with no waste of materials, thereby enabling goods of this character to be marketed at comparatively low cost and also in the most sanitary manner.

110 What I claim as new and desire to secure by a patent of the United States is:

115 1. In a machine of the character described, feed mechanism comprising an endless carrier having an operative stretch arranged adjacent to a web of material to be fed, a plurality of grippers mounted on said carrier, and having relatively stationary and movable jaws which are adapted to receive an edge of the web between them, said stationary jaw being fixed on the carrier and said movable jaw consisting of a rotatable rod journaled on the carrier and provided with high and low peripheral faces and to be moved alternately opposite the companion 120 stationary jaw, closing and opening tappets projecting laterally in opposite directions from said movable jaw rod, and closing and opening trip members arranged in the path 125 of said closing and opening tappets and to 130

successively turn said gripper rod for closing and opening the respective gripper.

2. A machine of the character described, comprising feed mechanism for pulling the end portion of a web of wrapping material wound in a roll into position for folding around a section of material to be wrapped, said feed mechanism comprising an endless carrier having an operative stretch arranged adjacent to said web, a plurality of grippers mounted on said carrier, opening means for opening the gripper after the same has completed a forward stroke, and closing means which are adapted to close the gripper before each forward stroke and which are controlled by the presence or absence of the material to be wrapped in a predetermined position.

3. A machine of the character described, comprising feed mechanism for pulling the end portion of a web of wrapping material wound in a roll into position for folding around a section of material to be wrapped, said feed mechanism comprising an endless carrier having an operative stretch arranged adjacent to said web, a plurality of grippers mounted on said carrier, and having relatively stationary and movable jaws which are adapted to receive an edge of the web between them, said stationary jaws being fixed on the carrier and said movable jaw consisting of a rotatable rod journaled on the carrier and provided with high and low peripheral faces and to be moved alternately opposite the companion stationary jaw, closing and opening tappets projecting laterally in opposite directions from said movable jaw rod, closing and opening trip members arranged in the path of said closing and opening tappets and to successively turn said gripper rod for closing and opening the respective gripper, and means for moving said closing trip member into and out of its operative position comprising a rock shaft on which said closing trip member is mounted, a rock arm on said shaft, a detector plate which moves into the path of the material to be wrapped and is moved out of said path when the material reaches a predetermined position, and a rod connecting said detector plate and said rock arm.

4. A machine of the character described, comprising feed mechanism for pulling the end section of a web of wrapping material wound in a roll into position for folding around a section of material to be wrapped, cooperating cutter mechanism for severing said web into sections, an endless carrier having an operative stretch arranged adjacent to said web, a plurality of grippers mounted on said carrier, opening means for opening each gripper after the same has completed a forward stroke, and closing means responsive only to the presence at a predetermined position of material to be wrapped, to close the

gripper about to enter on its forward stroke.

5. A machine of the character described, comprising means for holding a web of wrapping material wound in a roll with its free end extending downward, sets of cooperating feeding jaws for grasping said depending end at a point above a wrapping position and carrying the same down below said position, cutter mechanism for severing successively wrapper sheets from the end of said web, opening means for opening each set of feeding jaws when it arrives below said wrapping position, closing means for closing each set of feeding jaws when it is about to enter upon its downward feeding stroke, and means for controlling said closing means in accordance with the presence or absence in a predetermined position of the material to be wrapped. 75

6. A machine of the character described, comprising feed mechanism for pulling the end section of a web of wrapping material wound in a roll into position for folding around a section of material to be wrapped, cooperating cutter mechanism for severing said web into sections, an endless carrier having an operative stretch arranged adjacent to said web, a plurality of grippers mounted on said carrier, opening means for opening each gripper after the same has completed a forward stroke, closing means for closing each gripper before each forward stroke, a detector plate movable into and out of the path of oncoming material, and connections between said detector plate and closing means whereby the presence of material at the detector plate causes the closing of the gripper at the beginning of its advancing stroke and the absence of said material at said plate allows that gripper to remain open.

7. A machine of the character described, comprising means for holding a web of wrapping material wound in a roll with its free end extending downward, sets of cooperating feeding jaws for grasping said depending end at a point above a wrapping position and carrying the same down below said position, cutter mechanism for severing successively wrapper sheets from the end of said web, opening means for opening each set of feeding jaws when it arrives below said wrapping position, closing means for closing each set of feeding jaws when it is about to enter upon its downward feeding stroke, a detector plate movable into and out of the path of oncoming material, and connections between said detector plate and closing means for causing the latter to close when material actuates said detector plate and to remain open when it does not.

8. A machine of the character described, comprising an endless carrier for positioning wrapper sheets at a folding position for folding around a section of material to be wrapped, said carrier having an operative stretch arranged adjacent to the edge of the

web of the wrapper sheet, a plurality of grippers mounted on said carrier, opening means for opening each gripper after it has completed a forward stroke, and closing means responsive to the presence at a particular point of material to be wrapped, to close the gripper about to enter upon its forward stroke.

9. A machine of the character described, comprising an endless carrier operative in a vertical plane to move wrapper sheets downward to a folding position for folding around a section of material to be wrapped, said carrier having an operative stretch arranged adjacent to one edge of the wrapper sheet vertically disposed, a plurality of grippers mounted on said carrier, opening means below said folding position for insuring open grippers at the lower end of their stroke, closing means above said folding position for closing grippers just before entering upon their downward stroke, and means for controlling said closing means only in case material to be wrapped is present at a predetermined position.

10. A machine of the character described, comprising an endless carrier for positioning wrapper sheets at a folding position for folding around a section of material to be wrapped, said carrier having an operative stretch arranged adjacent to the edge of the web of the wrapper sheet, a plurality of grippers mounted on said carrier, opening means for opening each gripper after it has completed a forward stroke, closing means for closing said grippers before each forward stroke, a detector plate movable into and out of the path of oncoming material, and connections between said detector plate and closing means whereby the presence of material at the detector plate causes the closing of the gripper at the beginning of its advancing stroke and the absence of said material at said plate allows that gripper to remain open.

45 11. A machine of the character described, comprising an endless carrier operative in a vertical plane to move wrapper sheets downward to a folding position for folding around a section of material to be wrapped, said carrier having an operative stretch arranged adjacent to one edge of the wrapper sheet vertically disposed, a plurality of grippers mounted on said carrier, opening means below said folding position for insuring open grippers at the lower end of their stroke, closing means above said folding position for closing grippers just before entering upon their downward stroke, a detector plate movable into and out of the path of oncoming material, and connections between said detector plate and closing means for causing the latter to close when material actuates said detector plate and to remain open when it does not.

12. In a machine of the character de-

scribed, feed mechanism comprising an endless chain carrier traveling in a single plane and having an operative stretch arranged adjacent a web of material to be fed in said plane, a plurality of grippers mounted on said carrier and extending outward therefrom approximately in said plane and each gripper having relatively stationary and movable jaws which are adapted to receive an edge of the web between them, said stationary jaw being fixed at its inner end to said carrier and extending outward therefrom and said movable jaw consisting of a rotatable rod having web-engaging cam surfaces thereon, the axis of said rod extending outward parallel to said stationary jaw, means for rotating said movable jaw about its axis to close a cam face of the movable jaw upon said stationary jaw, to grip the web before beginning each feeding advance of the web, and means for rotating said movable jaw about its axis to move said cam face into open position relative to said stationary jaw after the completion of each feeding advance of the web.

In witness whereof, I hereunto subscribe my name this 2nd day of April, A. D. 1929.

EDWARD C. HEGG.
